VACUUM TUBE FILAMENT STRUCTURE

Lee Sutherlin, East Pittsburgh, Pa., assignor to
Westinghouse Electric & Manufacturing Company, a corporation of Pennsylvania

Application November 10, 1922
Serial No. 599,984

15 Claims. (Cl. 250—27.5)

My invention relates to evacuated electric devices, having particular relation to the cathode structure of such devices.

One object of my invention is to provide a vacuum-tube device embodying a filament construction wherein the filament is excited from alternating-current sources of energy without the introduction of the usual so-called "alternating-current hum" in the operation of the device.

Another object of my invention is to provide a cathode structure embodying such design as to avoid the usual microphonic action hereinbefore observed in most vacuum-tube devices.

A further object of my invention is to provide a cathode structure which is characterized by its rigidity of construction and efficiency of operation and by the absence of adjusting springs heretofore employed to compensate for the expansion and contraction of the filament.

Heretofore, considerable difficulty has been experienced in the excitation of the cathode element of detecting and amplifying vacuum tubes of the three-electrode type by alternating currents of commercial frequency because of the periodic variation in the voltage-current characteristic of the tube, resulting in the so-called "alternating-current hum" in telephone devices associated therewith.

A further disadvantage of many types of vacuum tubes heretofore employed consists in the microphonic action observed in the operation of the tube when the same is jarred. Such microphonic action may take the form of a sustained note of several minute duration and may be detected in the telephone receivers associated with the plate-filament elements of the tube.

I have found that the difficulties heretofore encountered in the excitation of vacuum-tube filaments by alternating currents of commercial frequency is mainly caused by the variations in the intensity of the magnetic field established by the exciting currents traversing the filament. I have further observed that the microphonic action is materially decreased by providing a loose support for the filament rather than a resilient support as has heretofore been the custom.

In practicing my invention, I provide a vacuum-tube device having a filament structure wherein the filament element may expand and contract without serious distortion, wherein the filament is so supported as to eliminate the microphonic action previously mentioned and wherein the disturbing effects of the periodic variations in the intensity of the filament-current magnetic fields are substantially avoided.

With these and other objects and applications in view, my invention further consists in the nature, the mode of operation and the constructional details hereinafter described and claimed and illustrated in the accompanying drawing, 30 wherein,

Figure 1 is an enlarged front-elevational view of an evacuated electrical device embodying my invention, a portion of the containing walls being broken away and the anode and grid elements 65 being shown in longitudinal section,

Fig. 2 is a front-elevational detailed view of the cathode structure shown in Fig. 1, and

Fig. 3 is a side-elevational view of the apparatus of Fig. 2. 70

In one embodiment of my invention, I provide an evacuated electrical device comprising an elongated tube 1 having a re-entrant portion 2 at one end thereof terminating in a supporting press 3. By way of illustration, a cylindrical anode 4 is 75 positioned in the tube 1 co-axial with the longitudinal axis thereof, the same being supported by carrier rods 5 and 6 extending from the supporting press 3. One carrier rod, say 6, may be extended through the press 3 to provide an external 80 terminal connection for the anode 4.

A grid 7 of helical shape is co-axially positioned within the space inclosed by the anode 4 and is supported by means of a carrier rod 8 which extends from the press 3 and engages the 85 helices of the grid 7. The carrier rod 8 may be extended through the press 3 to provide an external connection for the grid 7.

A filament 9 is constructed in the form of a U and comprises a bent portion 11 and parallel-extending bent-back portions 12 and 13. The filament 9 is positioned in the common longitudinal axis of the grid 7 and of the anode 4 and has its terminals secured to supply rods 14 and 15 extending from the press 3. The supply 95 rods 14 and 15 may be extended through the press 3 to provide external terminal connections for the filament 9.

The two sections or bent-back portions 12 and 13 of the filament 9 are positioned with a minimum space therebetween in order that the magnetic field established by currents in the one section may substantially neutralize the magnetic field established by currents in the other section, thereby providing a filament which lends itself 100 to excitation by alternating currents without the usual variations in the voltage-current characteristic of the device. The sections 12 and 13 may be insulatingly separated by a flat strip 16 of mica or other insulating material having a small 110

groove or indentation 17 at one end engaging the bent portion 11 of the filament 9.

The filament 9 may or may not be made to adhere to the insulating strip 16, depending upon 5 the particular means employed for imparting rigidity and ruggedness to the filament support as a whole. If the filament 9 is of the so-called "ribbon type", the flat sides of the filament sections are placed next to the insulating strip 10 11 in order to make the average distance between the filament sections or branches as small as possible. The insulating member 16, which has been shown in the drawing in the form of a mica strip, may be supported independently of the 15 means for supporting the filament, or the insulating material may be supported and then used as a filament support.

In the drawing is shown one arrangement 20 wherein the insulating material 16 serves as a support for the filament 9, in addition to insulatingly separating the branches 12 and 13 of the filament. The desired result is accomplished by providing the end of the insulating strip 16

25 adjacent to the bent portion 11 of the filament 9 with oppositely extending arms 18 and 19 which engage the unsupported end of the anode 4. In such construction, the filament 9 is supported at a single point where the indented portion of the insulating strip 16 engages the bent portion 30 11 of the filament 9. The filament 9, however, is preferably supported on the filament-supporting member 16 in a fairly loose condition, thereby minimizing the microphonic noises characteristic of the usual type of vacuum-tube construction.

35 While I have described, in detail, a certain specific embodiment of my invention, and while I have pointed out certain of the most obvious principles thereof, I do not intend that the language employed in the appended claims shall be limited to the precise features described, but I 40 intend that the claims shall be construed to cover all combinations which are fairly included in the language thereof, when read in connection with the prior art, regardless of the details and functions mentioned in the description or illustrated in the drawing.

I claim as my invention:

1. In combination, an insulating support having opposite faces, and a cathode element having 50 parallel extending sections carried by said support each of said opposite faces having one of said parallel sections disposed adjacent thereto.

2. A cathode structure for a thermionic device including a filament, comprising successive 55 parallel sections serially connected, a filament support comprising a longitudinally extending portion insulatingly separating the individual sections of said filament, said support having laterally extending portions forming supporting arms.

3. A cathode structure for a vacuum tube comprising a filament, a thin insulating member having a longitudinally extending portion and a pair of laterally extending arms, said member 65 being indented at one edge, said filament passing through said indentation from one face of said insulating member to the other and the sections of said filament meeting at said indentation being close to said faces and parallel to each other 70 whereby said sections are in minimum spaced relation.

4. An evacuated electric device comprising an enclosing envelope having a press, an anode, means extending from said press for supporting 75 said anode, a member having a longitudinally

extending portion symmetrically disposed with respect to said anode and also having laterally extending portions engaging said anode, said anode constituting a support for said member, and a filamentary element carried by said member.

5. A space-current device comprising an envelope enclosing an anode, a filamentary cathode having adjacently disposed sections and a bent portion connecting them, and an insulating member 80 separating said cathode, said insulating member having an end portion engaging said cathode at the bent portion thereof, and arms extending from said insulating member and engaging said anode, whereby said filamentary cathode is supported by said anode.

6. A space-current device comprising an envelope enclosing a cylindrical anode, a longitudinally extending member having opposite faces, integral extensions from said member positioning the member substantially in the axis of said anode, and a filament carried by said member and having portions disposed adjacent to said opposite faces.

7. A space-discharge device comprising an envelope 100 enclosing a cylindrical anode having opposite ends, a filament having two successive parallel sections disposed in the longitudinal axis of said anode, insulating means for maintaining said sections in such spaced relation that the 105 magnetic field established by currents traversing one section substantially neutralize that established by the currents traversing the other section, and integral extensions from said insulating means for engaging one end of said anode, where- 110 by said filament may be supported.

8. A space-discharge device comprising an envelope enclosing a cylinder-like anode having opposite ends, a filament having two successive, parallel sections disposed in the longitudinal axis 115 of said anode, a strip of mica interposed between said sections for insulatingly spacing the sections in such manner that the magnetic fields established by currents traversing the sections balance, and integral extensions from said strip 120 for engaging said anode, whereby said filament is insulatingly supported.

9. A vacuum tube enclosing a cylindrical anode, a sheet of insulating material having a longitudinally extending portion and a transversely ex- 125 tending portion and having its longitudinal member within the anode and its lateral members resting on the top of the anode and a filament supported by said sheet of insulating material.

10. A vacuum tube enclosing a cylindrical 130 anode, a sheet of insulating material having a longitudinally extending portion and a transversely extending portion and having its longitudinal member within the anode and its lateral members resting on the top of the anode, and a filament 135 mainly within said anode and extending across the top of said member.

11. A cathode structure comprising a filament support, a non-inductive filament rigidly carried thereby and closely adjacent thereto whereby heat 140 interchange may occur between said filament and its support.

12. A vacuum tube enclosing a plurality of electrodes including a substantially non-inductive filament therein, an insulating body non-micro- 145 phonically supporting said filament and means for applying alternating current for heating said filament whereby the insulating body will receive heat from said filament.

13. A vacuum tube enclosing a plurality of elec- 150

trodes including a substantially non-inductive filament therein, an insulating body non-microphonically supporting said filament and closely adjacent thereto, and means for applying alternating current for heating said filament whereby the insulating body will receive heat from said filament.

14. In a vacuum tube, a filament heated by alternating current, a filament support of insulating material having a greater specific heat than the filament, said filament being of substantially non-inductive shape and the spacing between

the filament and the body of the support being so close that the interchange of heat between the filament and the support will tend to obliterate the variations in electron emission arising from the periodic character of the heating current. 80

15. A cathode structure for a vacuum-tube device comprising a sheet of mica, a U-shaped filament having its arms closely adjacent to the faces of the mica and non-microphonically supported thereby. 85
